UNITED STATES PATENT OFFICE.

JAMES H. BRITTAINE, OF SALT LAKE CITY, UTAH.

ORE-CONCENTRATOR.

1,224,066.

Specification of Letters Patent. Patented Apr. 24, 1917.

Application filed April 6, 1916. Serial No. 39,493.

To all whom it may concern:

Be it known that I, JAMES H. BRITTAINE, a citizen of the United States, residing at Salt Lake City, in the county of Salt Lake and State of Utah, have invented certain new and useful Improvements in Ore-Concentrators; and I do declare the following to be a full, clear, and exact description of the invention, such as will enable others skilled 10 in the art to which it appertains to make and use the same.

My invention relates to improvements in ore concentrators and more particularly to those which include receptacles to which the 15 ore in suspension is fed and highly agitated and aerated in the presence of appropriate froth-forming liquids, the ore laden froth being allowed to overflow into one or more launders.

20 The object of the invention is to improve upon the general construction of concentrators of the class set forth to such an extent as to provide a comparatively simple and inexpensive machine which will produce a 25 maximum amount of work with minimum power.

With the foregoing general object in view, the invention resides in certain novel features of construction and in unique combinations of parts to be hereinafter fully described and claimed, the descriptive matter being supplemented by the accompanying drawings which constitute a part of this application and in which:

35 Figure 1 is a side elevation partly in section of the improved concentrator;

Fig. 2 is a horizontal sectional view thereof taken on the plane indicated by the line 2-2 of Fig. 1;

40 Fig. 3 is a vertical transverse section on the plane of the line 3-3 of Fig. 1;

Fig. 4 is a detail longitudinal section as seen on the plane indicated by the line 4-4 of Fig. 2.

45 In specifically describing the construction shown in the drawings above briefly described, similar characters will be employed to designate corresponding parts throughout the several views and reference will be here-
50 in made to the numerous elements by their respective indices. To this end, the numerals 1 designate a plurality of receptacles disposed side by side, all of said receptacles being preferably built in one unit provided
55 with upright sides 2 and partitions 3 extending therebetween and above the upper edges

thereof. Near its lower end, each receptacle 1 is provided with one or more inlet openings 4, two of such openings being here shown for each receptacle disposed in the 60 sides 2. Each receptacle 1 is also provided with a pair of waste outlet openings 5 also formed in the sides 2 and controlled by appropriate gates or valves 6.

Leading to the inlet 4 of one of the end- 65 most receptacles 1, is a conduit 7 adapted to conduct ore in suspension thereto, while leading from the outlets 5 of the numerous receptacles to the inlets 4 of adjacent receptacles, are additional conduits 8 disposed 70 on the exterior of said receptacles. The outlet 5 of the receptacle at the end of the machine opposite the supply conduit 7 is provided with a final discharge trough or the like 9.

Extending transversely across the lower 75 end of each receptacle 1, is an inlet conduit 10 whose opposite ends communicate with the inlets 4, each of these conduits having a discharge opening 11 in its bottom beneath 80 which a rotary agitator or impeller 12 operates, these impellers being preferably carried by upright shafts 13 driven in any preferred manner. This arrangement will forcibly agitate the ore in suspension which has 85 been properly treated for this purpose and will form a froth on the body of ore in the numerous receptacles, which froth will overflow from the upper edges of the sides 2 into launders 14. The waste, however, will 90 be discharged through the outlets 5 of the numerous receptacles and will be fed through the conduits 8 into the adjoining receptacles in which it will be retreated. The 95 ore in suspension is drawn into the machine by the impeller 12 in the compartment 1 into which the conduit 7 discharges, and in order that this ore may be sufficiently aerated, said impeller is underloaded, thereby causing it to draw into its receptacle a sufficient quantity of air to produce the desired results. By operating the machine in this manner, the usual aerating pump may be omitted. It is also of importance that the 100 conduits 8 be oversize in order that free air circulation may take place therein, and that the upper ends of these conduits be opened to still further facilitate such circulation (see Fig. 3).

The launders 14 are spaced laterally from 110 the sides of the machine beyond the conduits 8, the inner sides of said launders be-

ing preferably secured in contact with the outer sides of said conduits as shown. To properly conduct the froth into the launders without allowing such froth to enter 5 the conduits 8, eave boards 15 incline downwardly from the upper edges of the sides 2 to the inner sides of the launders; and in order that the froth may be directed properly onto these boards, deflecting plates 16 10 incline upwardly and outwardly from the longitudinal centers of the receptacles 1 to points spaced above the upper edges of said boards. Below the boards 15, pipes 17 extend longitudinally above the conduits 8 15 for the injection of suitable chemicals therein while separating the ore.

The launders 14 are provided with longitudinally extending vertical partitions 18 of less height than their sides, whereby said 20 launders are each divided into an outer chamber 19 and inner chamber 20. The ore laden froth may be directed into either the inner or outer chambers by proper disposition of cover plates 21 which when disposed 25 as shown in full lines in Fig. 3 will direct such froth into the outermost chambers 19, since said plates are disposed over the tops of the chambers 20 and incline downwardly from the boards 15 to the upper edges of 30 the partitions 18. When, however, the plates 21 are moved to the dotted line positions indicated in Fig. 3, they will prevent the entrance of froth into the chambers 19 and direct the same into the chambers 20. 35 For holding the plates 21 in either position, they are provided with stop shoulders 22 on their lower sides which abut the partitions 18, said shoulders being preferably in the form of angle iron bars extending throughout the lengths of said plates.

If it is found that retreatment of the ore will be necessary, the froth may be directed into the innermost chambers 20, from which it may be conducted into the conduits 7 and 45 8 through passages 23 and 24 respectively, the former being in the form of ports extending through the inner walls of the launders 14 and the outer walls of the conduits 8, while the passages 24 are preferably in 50 the form of closed chutes extending from the lower end of the inclined bottom of the launders. All of the passages in question are equipped with valves or gates 25 whereby they may be opened and closed at will to 55 conduct the previously separated material into any compartment 1 desired.

In operation, the ore in suspension together with a sufficient quantity of air is drawn into the first compartment 1, this ore 60 being either now or previously treated with the proper froth-forming materials. As it is discharged from the outlet 11 of the inlet conduit 10 in this compartment, the ore will be violently agitated and thrown outwardly 65 and upwardly by the impeller 12. This agi-

tation causes the froth to form on the solution, which froth carries with it the concentrates and overflows into the launders 14. The waste, however, will be discharged from the outlets 5 of the first compartment 70 1 and will thus be fed into the inlet conduit of the second compartment. In this compartment the same action above described takes place, this operation being performed successively until the end of the 75 machine is reached and the final waste is discharged through the chute 9. As occasion may demand, while operating the machine, the cover plates 21 will be adjusted to direct the concentrates into the proper 80 chambers of the launders 14.

By constructing the improved machine in the manner shown and described, it will be highly efficient and durable in spite of the fact that it is extremely simple and inexpensive, these being salient characteristics in any machine of this class.

In conclusion, I will state that although certain specific details have been shown and described for illustrative purposes, changes 90 may be made within the scope of the invention as claimed without sacrificing the main advantages thereof.

I claim:

1. An ore concentrator of the class described including a pair of receptacles each having an inlet into its lower end and a waste outlet from its upper end, a conduit for supplying ore in suspension to the inlet of one receptacle, agitators in the lower ends 95 of both receptacles, a second conduit leading from the waste outlet of said one receptacle to the inlet of the other, said second conduit having an open upper end to allow free circulation of air, a launder spaced laterally 100 from the receptacles beyond said second conduit, and an eave board extending from one edge of the receptacles over the open end of said second conduit to the launder.

2. An ore concentrator of the class described comprising an agitating receptacle, said receptacle being provided with a side wall over which ore laden froth may overflow, a launder to receive such froth, said launder having a vertical partition dividing 115 it into two chambers, means for closing the upper end of either chamber to direct the froth into the other and return means connecting one chamber of the launder with the agitating receptacle.

3. An ore concentrator of the class described comprising an agitating receptacle, said receptacle being provided with a side wall over which ore laden froth may overflow, a launder to receive such froth, said 125 launder having a vertical partition dividing it into two chambers, a shiftable inclined cover plate for closing the upper end of either chamber to direct the froth into the other and return means connecting one 130

chamber of the launder with the agitating receptacle.

4. An ore concentrator of the class described comprising an agitating receptacle, 5 said receptacle being provided with a side wall over which ore laden froth may overflow, a launder to receive such froth, said launder having a vertical partition lying parallel to the aforesaid side of the receptacles and dividing said launder into two 10 chambers, said partition being of less height than the sides of the launder, an inclined cover plate having near its lower edge a stop shoulder, said plate being adapted to 15 incline upwardly from the upper edge of the partition to either side of the launder, the stop shoulder serving to abut said partition to hold the plate in either position and return means connecting one chamber of the 20 launder with the agitating receptacle.

5. An ore concentrator of the class described comprising a pair of receptacles each having into its lower end an inlet and near its upper end an outlet, a conduit for supplying ore in suspension to the inlet of one receptacle, agitators in both receptacles, a second conduit leading from the outlet of said one receptacle to the inlet of the other, one side of both receptacles being comparatively 25 low, a launder adjacent this side of the receptacles in which ore laden froth overflowing therefrom may collect, said launder having a partition dividing it into an inner and an outer chamber, a valved 30 passage leading from one of said chambers into the first named conduit, and means for directing the froth into either of said chambers.

6. An ore concentrator of the class described comprising a pair of receptacles each having into its lower end an inlet and near its upper end an outlet, a conduit for supplying ore in suspension to the inlet of one receptacle, agitators in both receptacles, a 45 second conduit leading from the outlet of

said one receptacle to the inlet of the other, one side of both receptacles being comparatively low, a launder adjacent this side of the receptacles in which ore laden froth overflowing therefrom may collect, said launder 50 having a partition dividing it into an inner and an outer chamber, a valved passage leading from one of said chambers into the first named conduit, and a cover plate for closing the upper end of either launder 55 chamber to direct the froth into the other.

7. An ore concentrator of the class described comprising a pair of receptacles each having an inlet into its lower end and an outlet near its upper end, a conduit for supplying ore in suspension to the inlet of one receptacle, agitators in said receptacles, a second conduit leading from the outlet of said one receptacle to the inlet of the other, both conduits being disposed adjacent one 60 side of the receptacles, the latter side being comparatively low, a launder adjacent this side of the receptacles in which ore laden froth overflowing therefrom may collect, said launder having a partition dividing it 70 into an inner and an outer chamber, a valved port formed through the adjacent walls of one chamber and the first named conduit, and means for directing the froth into either chamber.

8. In an ore concentrator, the combination of an agitating compartment, a subdivided launder for receiving the froth from said launder, shiftable means for directing the froth into either division of said launder, and return means connecting one division of said launder with the agitating compartment.

In testimony whereof I have hereunto set my hand in presence of two subscribing witnesses.

JAMES H. BRITTAINE.
